US00D948410S

(12) **United States Design Patent** (10) **Patent No.:** **US D948,410 S**
(45) **Date of Patent:** **** Apr. 12, 2022**

(54) **OPERATING PLATFORM**

(71) Applicant: **SICHUAN GOLDEN RIDGE INTELLIGENCE SCIENCE & TECHNOLOGY CO., LTD.**, Sichuan (CN)

(72) Inventors: **Jiaxin Li**, Chengdu (CN); **Weirong Liu**, Beijing (CN); **Yin Jiao**, Gothenburg (SE); **Li Yan**, Gothenburg (SE)

(73) Assignee: **SICHUAN GOLDEN RIDGE INTELLIGENCE SCIENCE & TECHNOLOGY CO., LTD.**, Chengdu (CN)

(**) Term: **15 Years**

(21) Appl. No.: **29/696,012**

(22) Filed: **Jun. 25, 2019**

(30) **Foreign Application Priority Data**

Dec. 27, 2018 (CN) 201830760862.3

CLAIM

The ornamental design for an operating platform, as shown and described.

DESCRIPTION

FIG. 1 is a perspective view of an operating platform showing our new design;

FIG. 2 is a front view of the operating platform;

FIG. 3 is a rear view of the operating platform;

FIG. 4 is a right view of the operating platform;

FIG. 5 is a left view of the operating platform;

FIG. 6 is a top view of the operating platform; and,

FIG. 7 is a bottom view of the operating platform.

The shade lines in the Figures show contour and not surface ornamentation.

1 Claim, 7 Drawing Sheets
